EXTERIOR BOMB CONTAINER
FOR AIRCRAFT

James C. Darnall, Hyattsville, Md.

Application November 8, 1943, Serial No. 509,375

10 Claims. (Cl. 89—1.5)

(Granted under the act of March 3, 1883, as
amended April 30, 1928; 370 O. G. 757)

1

The present invention relates to exterior bomb containers which are carried exteriorly beneath bombing aeroplanes, and usually by a single point of suspension on a bomb rack mounted on the plane, so that in case of emergency the whole bomb container with its load of bombs can be quickly separated from the aeroplane.

In some types of bomb containers, the release of the bombs therein is accomplished by a mechanical device, which is usually manually controlled and operated from an operating device within reach of the occupant of the aeroplane. In others the bombs are released by a push-button or other electrical device within easy reach of said occupant of the plane. The present invention is of the latter or electrically operated and actuated type of device.

The present bomb container comprises a metal shell in the shape of a closed cylinder having rounded front and rear ends, and provided with several pairs of opposed swinging hinged doors operated by gravity and mounted beneath the container. One of the features of the invention then consists in the means or arrangement of elements used to automatically close the doors and hold them closed after the bombs carried in the container have been discharged, in order to place the doors in a non-protruding position beneath the container. The purpose of closing the doors is to reduce the wind resistance of the container as the aeroplane speeds through the air.

Another feature of the present invention is a door locking and releasing mechanism by means of which the doors on the bottom of the bomb container are positively locked at first, and thereafter the locking latches are retracted by successive energizations of a solenoid, which enables the doors to swing by gravity on their hinges so that the bombs in the container may be discharged therefrom.

The container is divided internally into forward and aft compartments, and each compartment is arranged to release all the bombs therein simultaneously. All the bombs in the second compartment may be released immediately after the first action, or can be carried indefinitely at the option of the operator in the plane. In other words, each group of bombs in the two compartments is released by separate electric impulses, which actuate the door locking and releasing mechanism used in the invention, as will be more fully explained hereinafter.

According to the present invention after the container has discharged or dropped its load of bombs, while the doors on the container are auto-

2

matically closed by a special-actuated door closing and holding mechanism, both the latter as well as the door locking and releasing mechanism are not arranged to be re-set for a new dumping or releasing action until they have been manually re-set after a new load of bombs are placed in the container compartments, which will be done after the plane has returned to its base.

Means are also provided to dump the container 10 and its contents all at the same time in case of an emergency. This feature is common to other types of bomb containers, but in this case the electric cable which extends from the plane to the forward end of the bomb container is readily 15 disconnected from the container by a pull of about eight pounds when the container is released and dropped from the plane. Said feature and others will also be explained in detail in this specification.

20 In the accompanying drawings forming part of this specification;

Fig. 1 is a side elevation of the bomb container, the means used for mounting it on an aeroplane, and the means for operating and releasing bombs 25 from the container, associated portions of the aeroplane being shown in dotted diagrammatic form in said view.

Fig. 2 is a longitudinal vertical partial section 30 on line 2—2 of Fig. 3, showing the interior of the bomb container.

Fig. 3 is a transverse vertical section through the bomb container taken on line 3—3 of Fig. 2, showing some parts of the door closing and holding mechanism, and the operational features of 35 the doors of the bomb container.

Fig. 4 is a partial horizontal longitudinal section of the container taken on line 4—4 of Fig. 3, showing some of the parts of the door closing and holding mechanism and part of the door 40 locking and releasing mechanism.

Fig. 5 is a transverse cross-section taken on line 5—5 of Fig. 2, showing some of the parts of the door closing and holding mechanism, with the doors of the container shown in open position 45 in broken lines.

Fig. 6 is a partial vertical transverse cross-section on line 6—6 of Fig. 2, showing parts of the door locking and releasing mechanism.

50 Fig. 7 is a partial front elevation on the rack and associated parts of the door locking and releasing mechanism, in a slightly different operating position than that shown in Fig. 6.

Fig. 8 is a partial front elevation similar to Figs. 55 6 and 7, with the various parts of the door locking

and releasing mechanism in a third position of operation.

Fig. 9 is a vertical sectional view of the door locking and releasing mechanism taken on line 9—9 of Fig. 6.

Fig. 10 is a partial horizontal section on line 10—10 of Fig. 9.

Fig. 11 is a horizontal section on line 11—11 of Fig. 9.

Fig. 12 is an enlarged view of a part of the mechanism shown in Fig. 6.

Fig. 13 is a partial longitudinal section on line 13—13 of Fig. 4, showing parts of the door closing and holding mechanism.

Fig. 14 is a fragmentary vertical section on line 14—14 of Fig. 4, showing a locking or holding pawl, forming part of the door locking and holding mechanism.

As shown in Fig. 1, the numeral 1 indicates the bomb container which comprises the subject matter of the present invention. The numeral 2 indicates in diagrammatic form the wing of an aeroplane. Numeral 3 indicates the aviator. Numeral 4 indicates an electric push-button near the pilot's fingertips, and on the end of an electric cable 5 which actuates the bomb container 1 and its constituent parts. The numeral 6 indicates the device which is used for arming the bombs and 6a is the cord operated thereby. These details are not part of the invention but are illustrated in Fig. 1. A release cord 7 which is used for disengaging the bomb container 1 when it is desired to free same completely from the airplane is operated by the lever 8 shown in Fig. 1. The bomb rack 8a is a special device which is not novel so far as the present invention is concerned, but the bomb container 1 is mounted at 9 on said bomb rack preferably at a single point of suspension so that when it is desired to completely sever the bomb container 1 with its load of bombs therein from the aeroplane, same is accomplished by means of the bomb rack 8a and its pertinent parts, which may be operated by cords 6a and 7 of Fig. 1 of the drawings.

The cable 5 is shown in Fig. 1 as entering the bomb container 1 at connector 11. Said cable is readily disengageable, usually by a pull of seven or eight pounds in tension and will disengage when the container 1 is dropped from the aeroplane. The separable band 10 is a container supporting strap which encloses the bomb container 1, its details being shown in Figs. 1 and 6.

The interior construction and parts of the bomb container per se are shown in Figs. 2 to 6 inclusive of the drawings. The said container 1 consists of a preferably metal circular shell 12, as shown in Figs. 3 and 5 of the drawings, and as shown in Fig. 1 is substantially tubular throughout its length and is provided with forward and aft rounded ends 13 and 14, as shown. As indicated in Figs. 3 and 5, the metal drum of shell 12 is able to be opened at the bottom by means of opposite doors 15, 16, 17, 18, which are hingedly mounted at points 19, 20 etc., to the said drum 12.

The interior of the container 1 is provided with a horizontally positioned wall 21 near the top of the drum 12 which is fastened by welding or riveting at 22, 23 to the wall of the drum, as shown fully in Fig. 5. Longitudinal division walls 24 to 28 inclusive are provided which are vertically disposed and adapted to contain vertical rows of bombs 29, 30 etc., as shown in Fig. 5. When the doors 15, 16, are in closed position, it is seen that horizontal plates 31, 32 and Z-plates 33, 34, which

are mounted on the inner face of the doors at 35, 36 supports the bombs 29, 30 etc., in position in the container.

Numerals 37, 38, 39 (Fig. 5) indicate a bungee cord 66 which is mounted at 40, 41 on the interior of the drum 12, for the purpose of expelling all the bombs of a compartment of the container as soon as the doors 15, 16 are swung open by gravity or otherwise to positions indicated at 42, 43, as is readily understood. As shown in Fig. 2, there are two such cords 66, passing through slots 66a in the vertical walls 24—28.

The bomb container 1 is divided into forward and aft compartments 44, 45, Fig. 2, and each compartment is operated independently of the other when it is desired to empty the bombs 29, 30 etc., in each compartment, as will be explained further. Between the adjacent end walls 46, 47 of compartments 44, 45 respectively, is positioned what has been designated the "Door locking and releasing mechanism," which is indicated generally by numeral 48 (Fig. 2). This mechanism, which is controlled by the electric cable 5 assists in the opening of doors of both compartments 44 and 45, as will be fully explained as the description proceeds.

There is a second mechanism indicated generally by the numeral 49 (Figs. 2, 4 and 5) which is designated as the "Door closing and holding mechanism," which closes and holds the doors on the container 1 shut after the bombs have been discharged from said container, as will be fully explained herein.

As shown in Fig. 2, the door releasing mechanism 48 is provided with a solenoid 50 having an armature 51 (see Fig. 6) which actuates a vertical camplate 52, the last being provided with a number of eccentrically shaped and positioned slots 53 and 54 near the bottom thereof. The doors 15 and 16 in the forward compartment 44 are normally held in locked and closed position by means of longitudinal rods 55, 55 shown in Figs. 2 and 5, each of which is carried by a pair of Z-plates 56, 57, mounted between the doors 15, 16 and the horizontal plates 31, 32. The parts 58 and 59 (Figs. 2 and 9) form stops for the longitudinal rod 55 and the locking latch 60. The rods 55, 55 are each mounted in the Z-plates 56 and 57, and springs 61 on each rod are compressed between plates 57 and annular stops 62 which are fixed to rods 55 near their inner ends, as shown. Each movable rod 55 also passes through the outer end wall plate 63 near the bottom (Fig. 2) of the container compartment at the point 64, and it is readily seen that when the locking latch 60 is retracted by the door releasing mechanism camplate 52, as will be further explained below, the spring 61 which abuts against the collar 62 and the Z-plate 57, will force the longitudinal rod 55 to move to the right, as seen in Fig. 2 in compartment 44, and thus the end of the rod at 64 is withdrawn into the interior of the compartment, and within the inner face of the wall 63. Similarly, as the locking latch 60 is withdrawn by the door releasing mechanism 48 towards its vertical camplate 52, the door 15 is enabled to act by gravity, and swing downwardly at the hinges 19 so that the bombs 29, 30, etc., will fall out of the compartment 44 when doors 15 and 16 take the open position at 42, 43 respectively, as will be readily seen from Fig. 5 of the drawings.

It will be observed that the locking latch 60 is withdrawn to the right, as seen in Fig. 2, until 75 the inner end 65 thereof is flush with the inner

face of the end wall 46 of the compartment 44. In this way the end of the rod 55 which is engagement with or abuts against the locking latch 60 is in the proper position to slide downwardly along the inner face of the wall 46, as is readily understood.

It will be noted that when the doors 15, 16 are opened that the bombs 29, 30 etc., will fall by gravity from the two compartments of the bomb container, but in order to insure that they are all discharged therefrom the bungee cord 66 which is under tension will insure the expulsion of all the bombs from the container chambers. Each time the solenoid 50 is actuated, the cam-plate 52 rises in one stage or step, and the solenoid 50 must be actuated twice to empty both compartments 44 and 45, as will be present explained. The latches 60 and 67 extend from horizontally sliding elements 68 and 69 respectively, which have pins 70 and 70a respectively projecting therethrough, and engaging the eccentric slots 53 and 54 respectively in the camplate 52. It will be seen (Fig. 2) that when the camplate 52 is raised, the pin 70 will be drawn to the right as it follows the sloped part of the slot 53, and that this action withdraws the latch 60 so that the end 65 thereof becomes flush with the inner face of the wall 46 of the compartment 44. When the camplate 52 is further elevated the pin 70 remains in the slot 53 which is now vertical during this part of its length but the locking tongue or latch 66 is not withdrawn any further than the point just described by the further elevation of the plate 52. When the locking latch 60 has been acted upon, as just described, it is evident that the longitudinal rod 55 is in proper position to permit the doors 15, 16 to open.

With reference to the locking latch 67, which holds the doors 17 and 18 of the aft compartment 45 closed, it will be seen that its pin 10a operates in the slot 54 of the vertical camplate 52 and as the plate 52 is elevated during the first portion of the travel of the pin in the slot 54 that the locking latch 67 is not retracted by the slot. During the second portion of the upward movement of plate 52 the pin 70a follows the inclined portion of the slot 54, and the locking latch 67 is retracted to the left, as seen in Fig. 2, thereby permitting the movable rod 55a to shift to the left under the thrust exerted by spring 61a from the locking latch 67 and thereby permit the door 18 of the container to open, as before described in connection with compartment 44.

Thus it will be seen that during the first portion of the upward motion of the plate 52 latch 60 is retracted to the right, as seen in Fig. 2, so that the bombs in compartment 44 will be discharged first or before those contained in the compartment 45. Also, upon the second step of the upward motion of the plate 52 the locking latch 67 is retracted to the left in Fig. 2 and the longitudinal rod 55a permits the doors in compartment 45 to open and discharge the bombs which are contained in said compartment. In other words, the discharge of bombs from compartments 44 and 45 takes place in sequence and not simultaneously when the door release mechanism is operated. Moreover, it will be evident from the following description that when a discharge of bombs has taken place from compartment 44, the bombs in adjoining compartment 45 may be retained indefinitely in the container and discharged whenever the aviator is ready to do so. It will be noted also that with the present device there is not provided means

for any release of individual bombs from either particular compartment of the container.

As will hereinafter be described in detail there is provided suitable mechanism for limiting the upward movement of the cam plate 52 to one-half of its complete stroke whenever the solenoid 50 is actuated by depressing the push button 4. This mechanism keeps the cam plate 52 from resuming its upward travel to release the bomb in the aft compartment until the push button 4 has been depressed a second time.

Door closing and holding mechanism

After the bombs have been discharged from either compartment, such as the fore compartment 44, it will be seen that it is quite necessary to close the doors 15 and 16 from their open positions 42, 43 (Fig. 5) in order to avoid great wind resistance along the under side of the bomb container 1, due to the speed of the aeroplane. In order to automatically shut these doors, which are the same in both compartments 44 and 45, a door closing mechanism described as follows has been adopted to accomplish the purpose.

As shown in Fig. 3 of the drawings there is a preferably continuous cord 71 which is attached to the door 16 at point 72 and proceeds over pulley 73, thence over pulley 74 and around horizontally disposed pulley 75, continues over vertical pulley 76 and downwardly over pulley 77, and the end is then attached at point 78 to the companion door 15 of the compartment 44. The same arrangement of parts, of course, is used on the opposite or aft end of the compartment 45 of the bomb container 1, but is not shown on the drawings, and what is said herein with regard to the door closing mechanism relative to compartment 44 will apply with equal force to the compartment 45 and its associated parts.

The pulleys 73 and 77 are mounted on the wall 63 of the drum 12, as shown in Figs. 2 and 3 of the drawings. The cord 71 passes through an aperture 79 in the forward end 13 of the container 1 and is attached to the door 15 as just described. The purpose of this aperture is to enable the cord 71 to be pushed inside of the container after the doors have been closed to take the position shown in Fig. 2, as said cord is comparatively loose when the doors are closed and the doors have been re-set in locked position, as will be described below.

The pulleys 74 and 76 are mounted in support 19a which is carried on the horizontal division wall 21 and the end wall 63 of the drum 12, as shown in Figs. 2 and 3 of the drawings.

The horizontally positioned pulley 75 is revolvably mounted on the end of a plunger rod 80, and the latter is carried in a sleeve support 81, and also carried in a bearing 83 which forms part 60 of a reciprocating carriage 82. Said carriage 82 is provided with two wings 84, 84 which ride along movably on a slide bar 85, which last has a rectangular cross-section and is rigidly mounted at points 111, 112 on the horizontally disposed division wall 21 of the container 1. Plunger rod 80 is surrounded by a spring 113 which is compressed between the bearing portion 83 of the carriage 82 and a shoulder 81a on the sleeve support 81.

The slide bar 85 is shown in Figs. 2, 4 and 13, and as best shown in Fig. 13, is stepped at 88, where the sleeve support 81 is rigidly mounted on slide bar 85. The plunger rod 80 is slidable in the sleeve support 81 and when free to do so can 70 be means of the release of spring 113 and car-

riage 82), move to the right to a position adjacent to nut 112, in which case the plunger rod 80 carries the pulley 75 with it by means of a clevis or shackle 89. When pulley 75 moves to the right it will pull cable or cord 71 which will then in turn close the doors 15, 16 (if previously in an open position as at 42,43, Fig. 5).

The carriage 82 is normally at the left end of its stroke as shown in Fig. 2, and spring 113 is compressed. A lug 100 on a trip lever 99 projects upward through an opening 101 in the slide bar 85 by an amount sufficient to retain the carriage 82 at the left end of its stroke and against the force exerted by the spring 113. The trip lever 99 is fixedly attached to a rotatable shaft 95 which is of substantial length and carried by a support 90 having upstanding leg portions 93 and 96 having bearings in which shaft 95 rotates. At the other end of shaft 95, remote from trip lever 99, is a lever 94, also fixed to shaft 95 so as to rotate with it.

A coil spring 129 surrounds shaft 95 near its left end, and has leg portions 130 and 131 bearing against the top of lever 94 and against the top of slide bar 85. The spring is so tensioned that it tends to rotate shaft 95 clockwise as viewed in Figs. 5 and 14, whereby the lug 100 on trip lever 99 will normally project upward through the opening 101.

A fastening 87 (Fig. 4), carries a pin or fulcrum rod 124 (Fig. 5) for a crank lever 86 (Fig. 5) having a substantially horizontal leg 91 which engages the end portion of lever 94. Another leg 92 of lever 86 extends substantially vertically downwards, where it is held against clockwise rotation by the bombs between vertical walls 27 and 28. The crank lever 86 is substantially channel shaped in cross-section.

A pin 98 passes through the opposite legs of the channelled lever 86 and supports a coil spring 102 having legs 103 and 104 which bear against the interior of the container shell 12 and the leg 92 of the crank lever 86 respectively. Spring 102 is so tensioned that it urges lever 86 clockwise about its pivot 124. The bombs prevent such movement until they are discharged, as mentioned in the last paragraph.

Upon release of the bombs however, spring 102 rotates lever 86 clockwise, leg 91 thereof raising lever 94, which turns shaft 95 so as to depress trip lever 99. The tooth or lug 100 is thereby withdrawn from the opening 101. Carriage 82 is propelled to the right by the compressed spring 113, and carries pulley 75 to the right, by which means the cord 71 is tensioned and doors 15 and 16 are closed.

As best shown in Figs. 1 and 2, brackets 105 and 106 are fastened to the doors 15 and 16 near their forward edge, and extend over the openings 79 in the forward end 13 of the container. The cord 71 passes through openings in the brackets and the ends thereof are fixed to the fastenings 72 and 78. The carriage 82 may be pulled to the left by pulling on the fastenings 72 and 78 since cord 71 can be pulled through brackets 103 and 106. During movement of the carriage 82 from left to right and back again, a plate forming the bottom of the carriage, indicated by 82 in Fig. 13 and by dotted lines 82a in Fig. 4, prevents interference between tooth 100 and the carriage during the carriage movement.

After the bombs are loaded into container 1, and crank lever 86 is pushed from its dotted line position into its normal position indicated by full lines in Fig. 5, the carriage 82 can be pushed

manually and returned to its normal or re-set position shown in Fig. 4, with the spring 113 placed under compression. The tooth or lug 100, again enters slot 101 in the slide bar 85, which holds the carriage 82, plunger rod 80 and pulley 75 in proper re-set position to close the doors 15, 16 in case they are again opened to discharge bombs.

The container 1 is placed upside down with the doors 15, 16 on the top when chambers 44, 45 are to be filled with bombs, in which case the bungee cord 66 (Fig. 5) is readily stretched or expanded and placed in the position shown, due to the weight of the bombs 29, 30 etc. assisting in the operation. Moreover, the crank lever 86 is more readily placed in its proper or re-set position when the container 1 is upside down, and this also assists the operator to place the projecting or locking tooth 100 into its slot 101 in the slide bar 85.

When the doors 15, 16 are closed (as above described by the door closing mechanism 49), they must be held in such position after reloading the container with bombs. This is done by means of a manual re-setting of the door releasing mechanism 48, so that same will push the locking latches 60 and 67 into protruding positions shown in Fig. 2, and thereby also push the longitudinal rods 55 and 55a into and through the slots at 64, in the vertical walls 63 of the container 1. This re-setting of the latches or locking tongues 60 and 67 is accomplished as follows:

When the solenoid 50 operates the vertical camplate 52 in an upward direction, pins 70 and 70a are drawn into positions as close as possible to the vertical center line 114 of the door releasing mechanism, as shown in Fig. 2. This pulls the locking latches 60, 67 out of engagement with corresponding apertures in the container walls 46, 47.

To re-set the vertical camplate 52 and the latches 60 and 67 into a locked position shown in Fig. 2 it is necessary to use a manual tool which will engage a hole 115 at the bottom of camplate 52 and pull the plate downward to the position shown in Fig. 2, whereby the pins 70 and 70a will follow their respective slots 53, 54 in plate 52, and the locking latches 60 and 67 will be pushed through the apertures in walls 46, 47 and into engagement with the ends of rods 55, 55a in the apertures at 64, in the walls 63 in locked positions, thus locking the container doors until they are reopened by actuating the push-button 4 of Fig. 1.

As mentioned previously, energization of the solenoid by the push-button switch 4 will raise the camplate 52 only through one-half of its vertical stroke, to discharge the bombs from the fore compartment 44. To discharge the aft compartment 45 the button 4 must be pressed a second time. The mechanism by which this is effected is shown in Figs. 2 and 6 to 12 inclusive.

Adjacent its bottom end the camplate 52 is guided by slots 107 and 108 in the sliding elements 68 and 69, and by rollers 109 and 110 which are journalled in the brackets 116 and 117. The rollers 109 and 110 also bear against the top surfaces of the sliding elements 68 and 69. Adjacent its upper end the camplate 52 is guided between spaced pairs of brackets 118 and 119 which are riveted to the compartment walls 46 and 47. Rollers 120 and 121 are journalled between the spaced brackets of each pair 118 and 119 on bolts

122 and 123, and also serve to guide the cam-plate 52.

The camplate 52 has a rack 125 with teeth 126 projecting from that side of the camplate which faces the solenoid 50. The armature 51 of the solenoid has a downwardly extending shaft terminating in a clevis 128. A clevis pin 130 passing through the clevis 128, also passes through the opposing vertical slots 133 and 134 at the extremities of legs 135 and 136 of the brackets 116 and 117. A washer 137 has an L-shaped cross-section, a horizontal leg 138 thereof having an opening through which the shaft 127 extends, and acting as a washer. A spring 139 surrounds shaft 127 and is compressed between the leg 138 and the solenoid 50, thus urging the armature 51 with the shaft 127 and the attached parts downward. The clevis 128 and clevis pin 130 are thus pulled upwardly by the action of solenoid 51 and pushed downwardly by the action of spring 139, with their normal position being down and pin 130 at the bottom of the aligned slots 133 and 134.

As shown in Figs. 2 and 6 the solenoid 50 is supported by a bracket 140 which is fastened to the horizontal walls 21 by the nuts 112. A tension coil spring 141 extending between bracket 140 and a lug 142 on camplate 52 constantly urges camplate 52 upwardly. The tripping means to be described now, prevents camplate 52 from moving upwardly under the action of spring 141 except when the tripping means is actuated by pressing push-button 4.

The opposite legs 135 and 136 of brackets 116 and 117 support a pin 143 which acts as a pivot for a pair of levers 144 and 145. As best shown in Figs. 9 and 11 the lever 144 is made up of a pair of identical members separated by spacers, which spacers also act as axles for rollers 146 and 147. Each member of lever 144 has a vertical leg 148 and another leg 149 extending at an angle of about 30 degrees from leg 148. Each member is pivoted on pin 143 at the juncture of its legs 148 and 149, and the two members are separated by the spacers-rollers 146 and 147 as previously described.

Lever 145 is pivoted on pin 143 between the spaced elements of lever 144. Lever 145 has three legs 150, 151, and 152 which are spaced approximately 90 degrees apart, leg 152 terminating in a tooth which engages the rack teeth 126 on the camplate 52. A coil spring 153 having legs 154 and 155 is also mounted on the pin 143, and is so tensioned that its legs 154 and 155 urge lever 144 counter-clockwise and lever 145 clockwise. The roller 146, separating the elements of lever 144 at its vertical leg 148, also engages the rack teeth 126.

When the camplate 52 is at the bottom of its stroke as in Fig. 6, the spring 153 urges the tooth on leg 152 of lever 145 and the roller 147 on lever 144 against the rack teeth 126. A hook 156 is pivoted at its upper end to the clevis pin 130. At its lower end 157 the hook engages leg 151 of lever 145. Near its mid-length the hook has a face portion 158 which is engaged by the roller 147 on leg 149 of lever 144. At its upper end the hook has a projecting lug 159 which engages the bottom of the vertical leg of the washer 137.

Upon actuation of the solenoid the hook 156 is pulled upwardly. Figs. 8 and 9 show two positions of the mechanism during the upward movement of the hook. Its lower end 157 engages leg 151 and rotates lever 145 counter-clockwise to disengage the tooth on its leg 152 from the rack teeth 126. The camplate 52 is thereby released

to move upward under the influence of spring 141, thus rotating lever 144 clockwise and disengaging roller 146 from the rack teeth. The clockwise movement of lever 144 is limited by a stop 160. 5 During the upward movement of the hook 156, its face portion 158 engages roller 147 which rotates the hook counter-clockwise about the clevis pin 130 and releases the leg 151 and the lever 145 from the hook 156. The movement of the hook in its rotation after its release is snubbed by engagement of its lug 159 with the spring pressed washer 137.

The spring 153 snaps levers 144 and 145 back again so that 152 and 146 engage the rack teeth 126 again to prevent the camplate 52 from moving upward by an amount greater than the distance of one rack tooth.

After the push-button 4 is released again, spring 139 moves the armature 51 and its associated parts down again, and the hook 156 resumes the position shown in Fig. 6.

When desired the vertical camplate 52 may be operated manually in an upward direction by inserting a hooked tool in triangular loop 160, 25 Fig. 6, through the aperture 161 provided in the shell or drum 12 of the container 1; and also the reverse motion on plate 52 may be made by a similar hand tool inserted in the hole 115 in plate 52, which actions are necessary while or when the cable 5 is disconnected from the container 1 and no power reaches solenoid 50; and also when refilling the container with bombs, the doors 15, 16 must be locked and the vertical camplate 52 re-set manually in order to accomplish this purpose.

Operation

It is assumed that the bomb container 1 has been loaded in compartments 44 and 45 with a full complement of bombs as shown in Figs. 2 and 40 5 of the drawings, and the doors 15 to 18 of the container 1 have been closed and locked by means of the latches 60 and 67 and by means of the longitudinal rods 55 and 55a being in engagement with the slots 64, 68 in the end walls 63, 63 of the container 1. The bomb container 1 is, of course, suspended at point 9 on the bomb rack 8a supported on the wing 2 of the aeroplane as shown in Fig. 1 of the drawings.

When it is desired to discharge the bombs from 50 the compartment 44, Fig. 2, the operator presses the push-button 4 which energizes the electric cable 5 which enters the bomb container 1 at point 11 and continues along the top of the compartment 44, Fig. 2, and reaches the solenoid 50. 55 The solenoid being energized draws the armature 51 upward and with it the camplate 52 by means of the apparatus shown in Figs. 6 to 11 of the drawings. Upon the energization taking place, as explained above in the specification, the rack 60 125, Fig. 6, is pulled upward the distance of one rack tooth 126.

Camplate 52 is thereby drawn upward a short distance equivalent to the inclined upper-half of 65 the slot 53. When this action takes place, the pin 70 is drawn inwardly toward the center line 114 of the camplate 52. The pin 70 being attached to the latch 60, withdraws said latch to the right and frees it from the stop 59 formed on the doors 15 and 16 of the container 1. The spring 61 on the longitudinal rod 55 is then free to come into action and forces the collar 62 and the rod 55 to the right as seen in Fig. 2. When the rod 55 is drawn to the right, the left end 70 thereof is retracted from the slot 64 in the inner

end wall 63 of the container 1, so that the rod is freed from the said wall 63.

The doors 15, 16 are then acted upon by gravity and swing on the hinges 19 and 20, Fig. 5, to the dotted positions 42, 43, respectively. The bungee cord 66 as well as the weight of the bombs 29, 30, etc., cause all the bombs in chamber 44 to be discharged from the container 1. When the bungee cord 66 has forced all the bombs from the container, the spring 102, Fig. 5, which is mounted on pin 98 causes the crank lever 86 to take the dotted position shown in Fig. 5, thereby pushing the end 91 of the crank lever 86 upward and into engagement with the lever 94. This causes the shaft 95 to revolve as before explained and disengage the tooth or lug 100 from the slot 101 in the slide bar 85.

This action allows spring 113 to push the carriage 82 along the slide bar 85 to the right. When the carriage 82 reaches the pivot or nut 112, the plunger rod 80 has been drawn to the right and with it the horizontal pulley 75, and the cable or cord 71, being mounted thereon, is also drawn to the right. In Fig. 3 it is seen that when the cord 71 is drawn upward by means of horizontal pulley 75 that the doors 15 and 16 are drawn upward from the dotted or open positions 42, 43 until they reach the periphery of the bomb container 1 and are in completely closed position.

The spring 113, Fig. 4 will ordinarily hold the door in these closed positions when the bomb container 1 is not loaded with bombs 29, 30, etc., thereby enabling the aeroplane to make its return to its base with the doors within the outline of container 1. When the container is loaded with bombs, however, the spring 113 will not be sufficient to overcome the weight of the bombs in the container and hold the doors closed.

With reference to the bombs which are in the compartment 45, Fig. 2 of the container 1 and the door locking and releasing mechanism 48, it was seen that upon the first energization of the electric cable 5 that the solenoid 50 raised the camplate 52 through a one-half length of the slot 53 in said plate 52. Upon a second energization of said cable 5, the camplate 52 is raised through the second or lower half of the slot 53, and it is evident that the pin 70 during this second movement operates through the vertical portion of said slot 53 and therefore is not drawn to the right or to the left by the last described operation of the camplate 52. However, with reference to the pin 70a, it is seen that during the first energization of the cable 5 and the camplate 52 that the pin 70a moves through a vertical portion of the slot 54 and accordingly, latch 67 was not retracted to the left as seen in Fig. 2.

During the second energization, however, the pin 70a will move through the inclined portion of the slot 54 and will follow said portion of the slot and move to the left toward the center line 114 of the plate 52 and accordingly, the latch 67 will be retracted to the left.

The longitudinal rods 55a will be withdrawn from the wall slot (not shown) corresponding to 64 in wall 63 of Fig. 2 and the doors 17 and 18 which close the chamber 45 are then free to fall downward by gravity and discharge the load of bombs in the compartment 45. By means of the apparatus just described, the bomb contents of chambers 44 and 45 are discharged from the container 1 in sequence, enabling the operator of the device to discharge or withhold the bombs in each compartment at his pleasure.

Attention is drawn to the fact that if the slot 75

54 is made similar to the slot 53 but opposite hand therefrom that the locking latches 60 and 67 will both be withdrawn at one and the same time, by a single energization of the solenoid 50 and upward motion of the camplate 52. In this case, it is seen that the discharge of the bombs from both compartments 44 and 45 can be made simultaneous. After the bombs have been discharged from both chambers of container 1 and the doors 15, 16, 17, 18 closed by the door closing and holding mechanism 49, the aviator makes his way to his home base so the container can be reloaded with bombs.

The reloading operation is as follows: The bomb container is freed from the plane at point 9, Fig. 1 and is turned upside down so that the doors 15 to 18 are on the top of the container. The spring 113, Fig. 2, is compressed manually until the tooth 103 is in engagement with the slot 101 in the slide bar 85 in which case the cable or cord 71 is no longer under tension and the doors can be readily opened manually. The camplate 52 can be manually operated as seen in Fig. 2 by inserting a hooked tool through aperture 161 and the triangular loop 160 shown in Figs. 6 and 2 near the top of the container 1; or said plate 52 can be drawn downwardly by inserting a hooked tool in the hole 115 of said camplate. This provides a manual operation of the door locking and releasing mechanism when the cable 5 is disconnected, for instance, at the point 11, Fig. 1 from the container 1.

When the container 1 has been turned upside down, it is seen from Fig. 5 of the drawings that the container can be loaded with bombs through the open doors 15, 16, etc., and the weight of the bombs will force the bungee cord 66 into extended position as shown in said Fig. 5. When the bombs have been loaded in the container, the crank lever 86 is readily pushed into the position shown by the full lines in Fig. 5, so the device is then in proper position to permit the locking latches 60 and 67 and longitudinal rods 55 and 55a to be placed in proper positions to fully lock the doors 15 to 18 inclusive. The container can then be mounted once more on the bomb racks 8a, Fig. 1 at point 9 and the cable 5 connected at point 11 with the container, and the aviator is ready for another expedition.

It has been noted above in the specification that in the event, for instance, of the aviator being followed by enemy planes and it is necessary to make a quick return to his base, that the whole container 1 can be discharged at once from the plane by the operation of the bomb rack 8a at the point 9. As soon as the container 1 is freed at point 9 from the bomb rack 8a, a slight pull of from 7 to 9 lbs. at point 11 disconnects the cable 5 at said point from the container. It is also pointed out that as all the bombs in the container are held together in one group and that the said bombs do not receive a twirling motion which is usually necessary to "arm" the bombs. Therefore when they reach terra firma they do not, as a rule, explode as this would be disadvantageous if said container full of bombs were discharged over the aviator's home or neutral territory.

The invention described herein may be manufactured and used by or for the Government of the United States of America for governmental purposes without the payment of any royalties thereon or therefor.

I claim:

1. In a device of the class described, a normally closed bomb container, a door hingedly

mounted on the bottom of said container, means operatively connected to said door for positively and releasably locking said door in closed position on the container, for the purpose of holding and discharging a load of bombs therefrom by gravity, door closing and holding means operatively connected to said door arranged to close said door after the discharge of a load of bombs from the container, and means operatively connected to said door closing and holding means and engageable by the bombs in said container for rendering said door closing and holding means inoperative while the bombs remain in said container.

2. In a device of the class described, a normally closed bomb container, a pair of doors hingedly mounted on the bottom of said container, door locking and releasing means operatively connected to said doors for positively locking the doors in closed positions on the container and for releasing the locking means operable by the aviator from the aeroplane on which the container is mounted, door closing and holding means operatively connected to said doors for holding and discharging a load of bombs from said container, tripping means engaging said door closing and holding means arranged while in one position to render said last-named means inoperative, means connected to said tripping means and engageable by the bombs in said container arranged to actuate said tripping means to a second position permitting said door closing and locking means to automatically close the container doors after a discharge of the bombs from the container by gravity, resilient means for positively discharging all the bombs in the container when the doors are in an open position, and means on the door closing means for holding the doors positively closed until a bomb reloading operation of the container is desired.

3. In a device of the class described, a bomb container, a pair of doors hingedly mounted on the container, door locking and releasing means within the container operatively connected to said doors, arranged to positively lock the doors until it is desired to open them, and then to withdraw the said locking means and permit the doors to be opened by gravity, electric means for operating the door releasing means, resilient means for positively insuring the complete discharge of all the bombs from the container, door closing and holding means operatively connected to said doors arranged to close the doors after a bomb discharging operation has taken place and to hold the doors in closed position within the outline of the container until a reloading of the container with bombs is desired, and means operatively connected to said door closing and holding means and engageable by the bombs in said container to render said door closing and holding means inoperative while the bombs remain in the container.

4. In an electrically actuated and operated bomb container, a closed container, a pair of opposed doors hingedly mounted on the bottom of the container, electrically actuated means operatively connected to said doors for positively and releasably locking said doors in closed positions on the container and to permit the opening of said doors and discharge of bombs by gravity, automatic door closing and holding means operatively connected to said doors arranged to operate after a load of bombs has been discharged from the container, said automatic door closing and holding means comprising a lever actuated means arranged to be re-set ready to co-act with

the door releasing mechanism when the latter has positively locked the doors in closed position on the container after a bomb reloading operation has been performed, and tripping means connected to said lever actuated means operable to latch said automatic means against operation, said lever being normally engageable by the bombs in said container to render said automatic door closing and holding means inoperative position.

5. In an electrically actuated and operated bomb container, a closed drum having forward and aft compartments formed therein, a pair of opposed doors hingedly mounted on the container for each compartment, electrically actuated and operated means operatively connected to said pair of opposed doors for positively locking and releasably holding the doors on each of the two compartments, said last mentioned means comprising a step-by-step releasing means arranged after a load of bombs has been discharged from one compartment, to release the doors in the second compartment for the discharge of bombs therefrom, automatic door closing and holding means operatively connected to said pair of opposed doors for each compartment, and means connected to said door closing and holding means normally engageable by the bombs in the compartment for rendering said last named means inoperative until the bombs have dropped from the compartment.

6. In an electrically actuated and operated bomb container, a closed container, a pair of opposed doors hingedly mounted on the bottom of the container, electrically actuated means operatively connected to said pair of opposed doors for positively and releasably locking said doors, comprising a solenoid mounted within the container having an armature connected therewith, a camplate arranged to co-act with and actuated by the said armature, having a pair of slots unsymmetrically disposed with reference to the vertical center line of said camplate, a pair of opposed locking latches, each having a pin thereon in engagement with one of the slots in the camplate, a pair of horizontally disposed longitudinal rods slidably mounted within the container, a spring on each of said rods arranged to hold same in operative contact with their respective operating latches, an inner end wall on each of the compartments of the container, each having an aperture therethrough and arranged to co-act with the end of each of the longitudinal rods to lock the doors of the container, door closing and holding means in duplicate operatively connected to each of said pairs of opposed doors within the container respectively, means connected to said door closing and holding means normally engageable by the bombs in said container for rendering said closing and holding means inoperative until the bombs have dropped from the container and arranged to close each pair of doors after a load of bombs has been discharged from the respective chamber, and manually operable means connected to each of said door closing means and door locking means respectively for re-setting each of said means when it is desired to reload the container with bombs.

7. In an electrically actuated and operated bomb container, a normally closed container, a pair of opposed doors hingedly mounted on the bottom of the container and which retain the bombs in the container, electrically actuated door locking and releasing mechanism for positively locking the said doors in closed positions on the

container, and for releasing the doors to empty the container of bombs, door closing and holding mechanism for automatically closing and locking the container doors after a bomb discharging operation, comprising a horizontally disposed division wall in the container, a slide bar mounted in said division wall having an aperture therethrough, a slidable carriage adapted to slidably operate along the slide bar, and having a housing thereon forming a plunger rod bearing, a sleeve support rigidly carried by said slide bar, a plunger rod slidably mounted in said sleeve support and fixed at one end to said plunger rod bearing, a coil spring on said plunger and compressed between said sleeve support and said plunger rod bearing, a horizontal pulley on the other end of the plunger rod, a cord mounted in the horizontal pulley, the ends of which are each fastened to one of the container doors for pulling said doors into closed positions on the container after a bomb discharging operation has been performed, a means for retracting the plunger rod and pulley carried thereon comprising a rotatable shaft mounted on the top horizontally disposed division wall of the container, a trip lever rigidly mounted on the end of the said shaft, a locking tooth on said trip lever normally operable to engage the slide bar aperture, a second lever rigidly mounted on said shaft, a pivoted crank lever having a spring for holding same in normal engagement with said second lever, and spring means for holding the trip lever in normal position with the said locking tooth in engagement with said slide bar aperture, said crank lever being operable to overcome said holding spring and operate said trip lever as soon as the last bomb has left the container, thereby releasing said spring and plunger rod and moving the horizontal pulley mounted thereon inwardly and causing the door cord to close and hold the container doors in closed position.

8. In an electrically actuated bomb container, a normally closed container having a horizontally disposed division wall therein, a pair of doors hingedly mounted on the container for opening the bottom of said container and discharging bombs by gravity, a door locking and releasing mechanism connected with said doors, and a door closing and holding mechanism comprising a trip lever fixedly mounted on a rotatable shaft carried by said division wall, a spring on said shaft for normally holding said trip lever in one position, a continuous door pulling cord having its ends attached to the ends of the said doors, a plunger rod slidably mounted on the top of said horizontally disposed division wall, a horizontally dis-

posed pulley on the end of the plunger rod about which said continuous cord operates, means for retracting the plunger rod to pull the horizontal pulley and the door closing cord inwardly and close the container doors after they have been opened and for holding the same in closed position thereafter, and means operated by said trip lever for actuating the said retracting means.

9. A door locking and releasing mechanism for a bomb container comprising a solenoid having an armature, a vertical camplate in co-acting relation with said armature, provided with a pair of unsymmetrically positioned and special shaped slots therein, a pair of bomb container door locking latches each having a pin in sliding engagement with one of said slots in said camplate, said camplate, slots and pins being operable to move said latches and retract same in sequence, and means for operating said solenoid and camplate to accomplish the above described purpose.

10. A door closing and holding mechanism for the doors of a bomb container, comprising a support to be mounted inside a container and having a hole therethrough, a plunger rod slidably mounted on said support, a spring operable to move said plunger rod in one direction, a pulley mounted on said plunger rod for movement therewith, a cable passing through said pulley and having its ends connected to the doors of the container, a trip lever pivotally mounted in said container and having a portion projecting through the hole in said support to latch said plunger against movement under the influence of said spring, a second lever pivotally mounted within said container and operatively connected to said trip lever, a spring mounted on said second lever tensioned to rotate said trip lever to withdraw said portion from said hole one arm of said second lever being engageable by the bombs in said container so as to maintain said plunger against movement until the bombs have been dropped from the container.

JAMES C. DARNALL.
